US00D996897S

(12) **United States Design Patent** (10) **Patent No.:** **US D996,897 S**
(45) **Date of Patent:** **** Aug. 29, 2023**

(54) **SPOUT**(71) Applicant: **Runway Blue, LLC**, Alpine, UT (US)(72) Inventors: **David O. Meyers**, Layton, UT (US);
John R. Omdahl, II, Lindon, UT (US);
Daniel Kendall Harden, Palo Alto, CA (US);
Elliot Lucas Ortiz, San Francisco, CA (US)(73) Assignee: **Runway Blue, LLC**, Alpine, UT (US)(**) Term: **15 Years**(21) Appl. No.: **29/842,537**(22) Filed: **Jun. 14, 2022****Related U.S. Application Data**

(63) Continuation of application No. 29/768,922, filed on Feb. 2, 2021, now Pat. No. Des. 955,166, which is a continuation of application No. 29/731,210, filed on Apr. 13, 2020, now Pat. No. Des. 911,104, which is a continuation of application No. 29/602,291, filed on Apr. 28, 2017, now Pat. No. Des. 884,416.

(51) **LOC (14) Cl.** ..... **07-99**(52) **U.S. Cl.**USPC ..... **D7/398**(58) **Field of Classification Search**

Primary Examiner — Andrew Kerr(74) *Attorney, Agent, or Firm* — Sterne, Kessler, Goldstein & Fox P.L.L.C.(57) **CLAIM**

The ornamental design for a spout, as shown and described.

DESCRIPTION

FIG. 1 is a top front perspective view of a spout, showing the claimed design;

FIG. 2 is a top rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate environmental structure and parts of the article that form no part of the claimed design.
